TREATING OIL WELLS

Joe K. Butler and Samuel A. Winkelmann, West Columbia, Tex., assignors, by mesne assignments, to Leo Clark Morgan, Wichita, Kans.

No Drawing. Application May 19, 1937,
Serial No. 143,460

12 Claims. (Cl. 252—3.55)

This invention relates to the acid treatment of an oil well for the purpose of rendering the oil sands more permeable and increasing the flow therefrom.

In the acidizing of oil wells, such as with inhibited hydrochloric acid, it is found that certain oil-bearing sands of high lime content will not satisfactorily react with the acid. This is frequently true, for example, of the Miocene sands throughout the Gulf Coast area. Consequently, attempts to clean calcareous material off of the screen and out of the pore-space in the sands by the use of acid have not proved satisfactory in numerous cases. Apparently coatings or films of oil about the particles of the sand afford the calcite particles protection against reaction with the acid. It is also believed that the poor results obtained from the treatment of such sands with raw acid are due to the formation of acid oil gums, by reaction of the acid with the oil to produce a complex gummy material. Such gums or other precipitates which may be formed clog the pore space of the sand, and decrease the effective porosity and permeability.

It is an object of the present invention to provide a method of acid treating an oil-bearing sand of this character so as to overcome the above noted objections, obtain an effective reaction of the acid with the calcareous material, and substantially increase the porosity of the oil-bearing sand and thereby increase the oil flow.

We have discovered that the protective oil films about the sand particles may be effectively removed by forcing into the well and into the adjacent sand a water solution of a chemical reagent which is effective to cause the oil to be taken up by the water solution, probably in the form of an emulsion. Suitable chemical reagents of this type are the alkali metal salts or soaps of sulfonic and naphthenic acids. Other water soluble fatty acid salts or soaps may be used, particularly the alkali metal soaps of sulfonated fats and fatty acids. These include natural fats such as tallow, olein, stearin and the like, which have been sulfonated by treatment with sulfuric acid. Likewise, sulfonated fatty acids formed by sulfonating stearic, palmitic, oleic, and lower fatty acids such as acetic, propionic and the like, are included. A very satisfactory and comparatively cheap material is the sulfonic sludge acid derived from the treating of petroleum oil with sulfuric acid. Chemicals of the above character also lower the surface tension of the water, so that it penetrates the sand more easily.

In accordance with the present invention, an

alkaline water solution of a soap of the character specified above is forced into the bore of the well and thence into the adjacent sand, to thereby remove the oil film from the sand particles. This is followed by flushing with water to remove the first solution together with the oil taken up thereby, and to leave the sand particles exposed for effective contact with acid. Following this, a charge of inhibited acid, such as inhibited hydrochloric acid, is forced into the well where it performs its work effectively in dissolving calcareous material and producing a solution of calcium chloride. This solution is removed by flushing with water.

The solution of the water soluble soap is maintained alkaline, such as by an excess of caustic soda or other alkali over that required for reaction with the fatty acid or sulfonated fatty acid employed. If the solution becomes acidic, a precipitate is formed which will decrease the porosity of the sand. There is also incorporated with the oil-removing or emulsifying reagent an alkali metal hexametaphosphate, including such compounds as sodium hexametaphosphate, potassium hexametaphosphate, lithium hexametaphosphate, and ammonium hexametaphosphate. The chemical formula usually ascribed to the hexametaphosphates is exemplified by that for the sodium salt (NaPO₃)₆. The latter is available commercially in a form which upon solution in water gives an alkaline reaction.

When one of the above metaphosphate compounds is combined with the water-soluble soap or oil-removing reagent, the latter is rendered immune to reaction with calcium and magnesium compounds which may be dissolved from the sand. If such a metaphosphate were not present, and calcium and magnesium ions are formed in the water solution used to flush off the oil film, then these calcium and magnesium ions will react with the soap to form insoluble calcium and magnesium soaps which precipitate within the sand, decreasing the porosity thereof. The hexametaphosphate has the property of segregating the calcium and magnesium ions in substantially non-ionized but water-soluble form. Although we are unable to give a theoretical explanation of this, we believe that the hexametaphosphate compound reacts with the undesirable calcium and magnesium ions, forming complex compounds which are only slightly ionized but which remain in water solution. The net result is that the oil film is effectively removed from the sand, while at the same time precipitation of oil gums and water-insoluble compounds within the sand is

avoided. The solution can then be flushed from the sand, which has thus been conditioned for the subsequent acid treatment.

As a specific example of our invention, a producing well was first treated with a mix consisting of 25 gallons of 18° Bé. hydrochloric acid (inhibited) and 25 gallons of fresh water to remove cement obstruction from the screen, and open up the well and sand for subsequent treatment. This was immediately followed by pumping in 25 gallons of fresh water to force out the preceding acid solution with contained reaction products. This was promptly followed by pumping in a solution prepared by dissolving in 3000 gallons of fresh water, the following constituents:

	Per cent
100# NaOH	0.4
62# sulfonic acid sludge	0.25
200# sodium hexametaphosphate	0.8

This was followed by pumping in 300 gallons of fresh water to flush out the previous solution. Finally there was pumped in a mix consisting of 1000 gallons of 18° Bé. hydrochloric acid (inhibited) together with 1000 gallons of fresh water.

The above solutions or liquids are pumped into the sand as continuously as possible, so that one solution or liquid follows the other in close succession into and through the oil-bearing sand adjacent the bore of the well. After all of the above solutions or liquids have been pumped into the well, the liquid remaining therein is allowed to remain about one hour to complete reaction, and then is removed by swabbing or flowing.

In the example set forth above, the oil well was converted from one making gas only, but from which oil would not flow, to one which produced 537 barrels of gross fluid per day, equivalent to 419 barrels of oil after deducting the water content. Attempts to acidize the well without the preliminary soap solution treatment had been ineffective to produce oil flow. In another test, the permeability of the sand, as calculated by the standard A. P. I. method with a Curtin-Clough permeability apparatus, was increased approximately 66% by the method of the present invention, whereas the permeability was decreased by simple acid treatment alone.

By the method of the present invention in which a chemical mixture is applied to the sand to remove the oil film preceding the treatment with acid, substantial advantages are attained. A relatively clean calcareous sand is presented for reaction with the acid. Production of acid oil gums and precipitation thereof in the sand are substantially avoided. The reaction of the hydrochloric acid with the calcium carbonate goes substantially to completion, and the solution of the water soluble calcium chloride is washed from the sand. The precipitation of insoluble calcium or magnesium soaps within the sand is avoided by the selective action of the hexametaphosphate. The sand is made more permeable to oils by reason of the washing with the chemical mixture. Silicic acid which may be formed is washed out with the treating solution and does not clog the pores. The pressure necessary for pumping the acid into the formation is reduced due to the increase in permeability after washing with the chemical mixture.

Obviously many modifications and variations of the invention as hereinbefore set forth may be made without departing from the spirit and scope thereof, and therefore only such limita-

tions should be imposed as are indicated in the appended claims.

We claim:

1. In the acid treatment of an oil well to increase the flow therefrom, the steps which comprise introducing into the well and the adjacent oil-bearing sand a solution of a chemical effective to remove the protective oil films from particles of the sand, said solution also containing a metaphosphate effective to inhibit the formation of calcium and magnesium ions so as to avoid precipitation within the sand of insoluble calcium and magnesium compounds, and then introducing into the well and the adjacent oil-bearing sand an acid to react with calcareous constituents of the formation from which the protective oil films have been removed.

2. In the acid treatment of an oil well to increase the flow therefrom, the step which comprises treating the well and the adjacent oil-bearing sand to remove the protective oil films about the particles of the sand prior to acid treatment thereof, with an alkaline water solution of an alkali metal soap and a hexametaphosphate.

3. In the acid treatment of an oil well to increase the flow therefrom, the step which comprises treating the well and the adjacent oil-bearing sand to remove the protective oil films about the particles of the sand prior to acid treatment thereof, with an alkaline water solution of an alkali metal soap of a sulfonated fatty acid and a hexametaphosphate.

4. In the acid treatment of an oil well to increase the flow therefrom, the step which comprises treating the well and the adjacent oil-bearing sand to remove the protective oil films about the particles of the sand prior to acid treatment thereof, with an alkaline water solution of an alkali metal soap of a mineral oil sludge sulfonic acid and a hexametaphosphate.

5. In the acid treatment of an oil well to increase the flow therefrom, the step which comprises treating the well and the adjacent oil-bearing sand to remove the protective oil films about the particles of the sand prior to acid treatment thereof, with an alkaline water solution of a water soluble emulsifying agent and an alkali metal hexametaphosphate.

6. In the acid treatment of an oil well to increase the flow therefrom, the step which comprises treating the well and the adjacent oil-bearing sand to remove the protective oil films about the particles of the sand prior to acid treatment thereof, with a water solution prepared by dissolving therein acid sludge from the treatment of mineral oil with sulfuric acid, an excess of sodium hydroxide over that required to neutralize the sulfonic acids of the sludge and sodium hexametaphosphate.

7. The method of treating an oil well to increase the flow therefrom, which comprises introducing into the well and the adjacent oil-bearing sand in the order stated an alkaline water solution of an alkali metal soap and a hexametaphosphate, flushing water, and inhibited hydrochloric acid.

8. The method of treating an oil well to increase the flow therefrom, which comprises introducing into the well and the adjacent oil-bearing sand in the order stated an alkaline water solution of an alkali metal soap of mineral oil sludge sulfonic acids and an alkali metal hexametaphosphate, flushing water, and inhibited hydrochloric acid.

9. The method of treating an oil well to increase the flow therefrom, which comprises introducing into the well and the adjacent oil-bearing sand in the order stated, a comparatively small amount of inhibited acid, flushing water, an alkaline water solution of an alkali metal soap and an alkali metal hexametaphosphate, flushing water, and the main quantity of inhibited acid, and then removing remaining liquid with contained reaction products from the well.

10. The method of treating an oil well to increase the flow therefrom, which comprises introducing into the well and the adjacent oil-bearing sand in the order stated a comparatively small amount of inhibited acid, flushing water, a water solution of a chemical effective to remove the protective oil films from the sand particles and an alkali metal hexametaphosphate, flushing water, and the main quantity of inhibited acid, and then removing remaining liquid with contained reaction products from the well.

11. In the acid treatment of an oil well to increase the flow therefrom, the steps which comprise introducing into the well and the adjacent oil-bearing sand a solution of a chemical adapted to remove protective oil films from par-

10 ticles of the sand, said solution also containing a metaphosphate effective to inhibit the formation of calcium and magnesium ions so as to avoid precipitation within the sand of insoluble calcium and magnesium compounds, then introducing flushing water into the well and the adjacent oil-bearing sand, and thereafter an acid adapted to react with calcareous constituents of the formation from which the protective oil films have been removed.

15 12. The method of treating an oil well to increase the flow therefrom which comprises introducing into the well and the adjacent oil-bearing sand, an alkaline solution of a chemical effective to remove the protective oil films from particles of the sand, said solution also containing a metaphosphate effective to inhibit the formation of calcium and magnesium ions so as to avoid precipitation within the sand of insoluble calcium and magnesium compounds, then introducing flushing water into the well and the adjacent oil-bearing sand, and thereafter an acid to react with calcareous constituents of the formation from which the protective oil films have been removed.
